UNITED STATES PATENT OFFICE.

JOHN D. RIPSON, OF ROCHESTER, AND ERICK G. SAMPSON, OF JAMESTOWN, NEW YORK,
ASSIGNORS TO ART METAL CONSTRUCTION COMPANY, OF JAMESTOWN, NEW YORK, A
CORPORATION OF NEW YORK.

SUPPORT FOR DRAWERS OF CABINETS, &c.

No. 884,525.

Specification of Letters Patent.

Patented April 14, 1908.

Application filed October 26, 1907. Serial No. 399,287.

To all whom it may concern:

Be it known that we, JOHN D. RIPSON, a resident of Rochester, in the county of Monroe and State of New York, and ERICK G. SAMPSON, a resident of Jamestown, in the county of Chautauqua, State of New York, have invented a new and useful Improvement in Supports for Drawers for Cabinets, &c.; and we do hereby declare the following 10 to be a full, clear, and exact description thereof.

Our invention relates to supports for drawers of cabinets, filing cases, etc., its object being to provide a simple and efficient form 15 of device by means of which the drawer is held in a horizontal position when withdrawn from the cabinet and so limited in its movement as to prevent its accidentally dropping when drawn out to its full length.

20 A further object of our invention is to provide a device of this character in which the parts are so arranged that the drawer may be freed from the support and lifted therefrom without the removal of any of the parts, 25 while at the same time the parts are readily accessible for removal in cases of repair.

Our invention comprises the novel features hereinafter set forth and claimed.

In the accompanying drawings Figure 1 is 30 a vertical section of the upper part of a cabinet with a drawer in elevation partly drawn from the cabinet, dotted lines showing the drawer pulled out full length and in position to be detached from the cabinet; Fig. 2 is a 35 section on the line 2—2 Fig. 1; Fig. 3 is an interior view of one of the sides showing the drawer withdrawn; Figs. 4, 5 and 6 are enlarged sections on the lines 4—4, 5—5 and 6—6, respectively, Fig. 3.

40 In the drawing the numeral 2 designates a portion of a cabinet or filing case provided with drawers 3. Secured to the inner side walls 4 of the cabinet are the Z-bars 6 and 7. These Z-bars together form the guide- 45 ways for the channel bars 8. These channel bars 8 have secured to one end thereof the plates 10 carrying the rollers 11. These rollers may be formed of fiber or steel as desired, and are mounted on the spindles 12. The 50 plates 10 are provided with the flanges 14 which are adapted to strike against the stop or cushion 15 at the inner ends of the Z-bars 7. The inner ends of the channel bars 8 are

upset as at 17 and secured within the channel at the end thereof is the cushion block 18 55 formed of leather or other suitable material. The plate 10 is also provided with the buffer 19.

Plates 20 are secured to the forward end of the sides of the case or cabinet, said plates 60 having the stops 21 adjacent to the ends of the Z-bars 7 and in the path of the buffer 19 on the plate 10. In this manner the withdrawal of the channels is prevented until the plates 20 are removed. Guide plates 22 are 65 secured to the plates 20 and secured to said guide plates by means of the spindles 24 are the idle rollers 25 upon which the channels are adapted to travel. The outer ends of the channels are upset as at 26 and secured with- 70 in the channels are the buffers 27. The outer ends of the channel bars have their flanges cut away as at 28 to permit of the removal of the drawer, as fully hereinafter set forth. The drawer has secured to its sides 75 the strips 30 and rollers 31 are secured to said strips by means of the spindles 32. These rollers are adapted to engage the channels of the channel bars and are adapted to travel back and forth therein. 80

When the drawer is in its closed position in the cabinet the ends of the plates 10 bear against the buffers 15 and the rollers 31 bear against the buffers 18 at the inner ends of the channel bars. When it is desired to withdraw the drawer the operator grasps the handle 35 at the front of the drawer and pulls on the drawer. The drawer moves out, the rollers 31 traveling in the channels until said rollers strike the front buffers on said 90 channel bars, whereupon the channel bars are withdrawn, the wheels at the inner ends thereof traveling in the guide formed by the upper and lower Z-bars 6 and 7. The drawer may be withdrawn in this manner 95 until the buffers 19 strike the stops on the plates 20, whereupon the further outward movement of the drawer is arrested. The drawer is then supported by the extended channel bars and is held in a rigid horizontal 100 position. In case it is desired to remove the drawer when in this position it is only necessary to bring the front pair of rollers 31 in line with the cut-away portions 28 of the channel bars, whereupon by lifting up on the 105 drawer the said rollers are released from the

channel bars and the entire drawer is freed and may be readily removed. In this manner we provide not only for a drawer support in which the drawer is held against accidental displacement when withdrawn but at the same time one in which the drawer may be entirely removed when desired without the necessity of removing any of the parts of the suspension device. In case it is desired to remove the channel bars for the purpose of renewing the wheels mounted thereon or for any other reason, it is only necessary to remove the plates 20 whereupon the channel bars may be readily removed without difficulty.

What we claim is:

1. In a device of the character described, the combination of a cabinet, filing case or the like, guides on the walls of same, a drawer, slideable channel bars moving in said guides, wheels carried by said channel bars moving in said guides, plates removably secured to the walls of said cabinet near the outer portion thereof, said plates having stops in the path of said channel bars, and slideable connections between said drawer and said channel bars.

2. In a device of the character described, the combination of a cabinet, filing case or the like, guides on the inner walls of same, a drawer, slideable channel bars moving in said guides, and stops in the path of said channel bars, projections on the outer walls of said drawer slidably engaging said channel bars, stops at the outer ends of said channel bars, said channel bars having cut-away portions in their flanges to admit of the passage of said projections therethrough to remove the drawer.

3. In a device of the character described, the combination of a cabinet, filing case or the like, guides on the inner walls of same, a drawer, slideable channel bars movable in said guides, stops in the path of said channel bars, wheels carried by said drawer engaging said channel bars, and stops on said channel bars in the path of said wheels.

4. In a device of the character described, the combination of a cabinet, filing case or the like, guides on the inner walls of same, a

drawer, slideable channel bars movable in said guides, stops in the path of said channel bars, strips on the outer walls of said drawer, wheels carried by said strips engaging said channel bars, and stops on said channel bars 55 in the path of said wheels.

5. In a device of the character described, the combination of a cabinet, filing case or the like, guides on the inner walls of same, a drawer, slideable channel bars moving in 60 said guides, stops in the path of said channel bars, wheels carried on the outer walls of said drawer, said channel bars having their flanges cut-away to release said wheels therefrom, and stops in the path of said 65 wheels.

6. In a device of the character described, the combination of a cabinet, filing case or the like, Z-bars secured to the inner walls of same forming guiding grooves, the upper 70 Z-bar extending beyond the lower, slideable supports moving in said grooves, plates secured to the walls of said cabinet having stops in front of said lower Z-bar in the path of said supports, and slideable connections between said drawer and said supports.

7. In a device of the character described, the combination of a cabinet, filing case or the like, Z-bars secured to the inner walls of same forming guiding grooves, the upper 80 Z-bar extending beyond the lower, slideable supports moving in said grooves, plates secured to the walls of said cabinet having stops in front of said lower Z-bar in the path of said supports, brackets carried by said 85 plate, idle rollers in said brackets, and slideable connections between said drawer and said supports.

In testimony whereof, we the said JOHN D. RIPSON and ERICK G. SAMPSON have 90 hereunto set our hands.

JOHN D. RIPSON.
ERICK G. SAMPSON.
